US0D1008735S

(12) **United States Design Patent** (10) Patent No.: **US D1,008,735 S**
(45) Date of Patent: ** Dec. 26, 2023

(54) **BLADE FOR A MICRO PUREE MACHINE**

(71) Applicant: **SharkNinja Operating LLC**,
Needham, MA (US)

(72) Inventors: **Ming Li Shi**, Guangdong (CN); **Xu Sheng Deng**, HuiZhou (CN); **Pushan He**, Shenzhen (CN); **Ping Chu**, Kowloon (HK)

(73) Assignee: **SHARKNINJA OPERATING LLC**,
Needham, MA (US)

(**) Term: **15 Years**

(21) Appl. No.: **29/895,614**

(22) Filed: **Jun. 23, 2023**

Related U.S. Application Data

(63) Continuation of application No. 29/872,598, filed on Mar. 15, 2023, which is a continuation of application (Continued)

(57) **CLAIM**

The ornamental design for a blade for a micro puree machine, as shown and described.

DESCRIPTION

FIG. 1 is a top/front/left side perspective view of a blade for a micro puree machine, showing our new design;

FIG. 2 is a bottom/rear/right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the blade that form no part of the claimed design.

1 Claim, 8 Drawing Sheets

Related U.S. Application Data

No. 29/814,197, filed on Nov. 4, 2021, now Pat. No. Des. 983,603, which is a continuation-in-part of application No. 17/139,567, filed on Dec. 31, 2020.
